UNITED STATES PATENT OFFICE.

TORVAL E. VIK, OF SHELTON, CONNECTICUT.

WIRE-STRAIGHTENER.

1,335,625.

Specification of Letters Patent. Patented Mar. 30, 1920.

Application filed June 4, 1918. Serial No. 238,193.

To all whom it may concern:

Be it known that I, TORVAL E. VIK, a citizen of the United States, residing at Shelton, in the county of Fairfield and State 5 of Connecticut, have invented new and useful Improvements in Wire-Straighteners, of which the following is a specification.

This invention comprehends generally improvements in that class of inventions known 10 as wire working machines and more particularly has reference to a wire straightener.

It is the primary aim and object of the present invention to provide a device of the above mentioned character designed for 15 straightening pieces of wire of various thicknesses.

It is an equally important object of this invention to provide a device of the above mentioned character wherein the main 20 frame is of a novel form and is designed to removably receive and adjustably accommodate a series of supporting disks through which the wire is drawn when the frame revolves.

More particularly the present invention 25 includes the provision of a series of supporting disks constructed to adjustably accommodate the wire receiving sleeves, suitable clamping means being incidentally mounted 30 in the disks for holding the sleeves in a set position.

It is the more specific object of this invention to provide improved means for removably holding the disks in position in the 35 frame; and also provide improved means for rotatably mounting the frame.

Among the other aims and objects of this invention may be recited the provision of a 40 device of the character described with a view to compactness, and in which the number of parts are few, the construction simple and the cost of production low and the efficiency high.

Other improvements and novel details in 45 the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made

without departing from the principle of operation of the various parts.

The invention is clearly illustrated in the accompanying drawings, in which: 60

Figure 1 is a perspective view of the device.

Fig. 2 is a longitudinal sectional detail thereof.

Fig. 3 is a transverse section of the invention, and. 65

Fig. 4 is a detail of the adjustable clamping means.

Similar characters of reference are employed in all of the above described views to 70 indicate corresponding parts.

Referring now, more particularly, to the accompanying drawings, there is provided a base 1 on the upper surface and near the respective ends of which are connected 75 standards 2, the latter terminating at their upper ends in bearings 3 while detachably connected to and coöperating with the bearings are bearing brackets 4.

A main supporting frame 5 is now employed 80 and is of a substantially rectangular configuration comprising spaced side bars 6 and curved ends 7, the latter having sleeves 8 connected thereto and extending in opposite directions therefrom serving in effect as substantial trunnions and being journaled 85 in the bearings 3 beneath the brackets. The sides 6 are desirably arcuate in configuration and provide in effect opposed channels 9 and these channel shaped sides are 90 formed near the ends with opposed transverse grooves 10. The channel shaped sides are provided with longitudinal series of opposed openings 11 also for a purpose that will be described. 95

Insertible in the opposed grooves 10 and receivable in the opposed channel shaped sides of the frame is a plurality of disks 12 each of which is formed with a radial slot 13 and also with alining threaded bores 14 100 and 15 which establish communication with the respective ends of the slot and the outer edge of the disk.

The improved means for holding the disks within the frame consists of a plurality of 105 set screws 16 which are adjustably mounted in the opposed openings 11 while the inner ends thereof are designed for frictional engagement with the peripheries of the disks.

With a view toward providing suitable 110 wire receiving means a pair of relatively long tubes 17 are telescoped within the

sleeves 8 and removably clamped in a set position by means of screws 18. Coöperating with the tubes 17 are a series of smaller or relatively short tubes 19 one of which is mounted in each of the disks 12.

- 5 For the purpose of clamping the tubes 19 in the disks a pair of opposed jaws 20 is disposed in each slot 13, the stems 21 of the jaws being journaled in circular recesses 22 10 formed in the adjacent ends of exteriorly threaded screw plugs 23, the latter being in turn adjustably mounted in the threaded bores 14 and 15. The outer ends of the plugs 23 are provided with kerfs 24 adapted to 15 receive a screw driver or the like so as to facilitate adjustment of the plugs relative to each other and consequent clamping of the adjacent tube 19 in a relatively rigid position with respect to the jaws 20.
- 20 The frame holding the disks is rotated by means of a sheave pulley 27 over which a suitable belt may be trained and driven from a suitable source of power not shown.

In the use of the invention, the number 25 of disks employed may be varied to suit the character of bend in the wire to be straightened. To vary the spacing between the disks, one or more disks may be omitted, for example the two disks on opposite 30 sides of the center disk. The tubes 19 in the outermost disk are preferably alined with the tubes 17 and alternate disks between the two outside also have their tubes 19 preferably alined with the tubes 17 and offset 35 from the axis of the tubes 17 respectively. The distance the offset tubes 19 are positioned from the centers of their respective disks is determined by the elastic limit of the wire to be straightened. These offset 40 tubes should not be positioned a distance from the center of the disks greater than this elastic limit. It is obvious that the screw plugs 24 provide for the adjustment

of the tubes 19 so that they may be eccentrically disposed in their respective disks. 45 The rotation of the frame by means of the pulley, after wire has been passed through the tubes 17 and through the tubes 19 in the several disks effects a distortion of the wire which is only temporary on that part of the 50 wire not already having a permanent bend. This because the distortion is not greater than the elastic limit of the wire. Immediately a piece of wire containing a permanent bend passes through the tubes, the distortion on this particular part of the wire is greater than the elastic limit and the bent portion of the wire is thus brought back to normal shape.

Having thus fully described the invention 60 what is claimed and desired to be secured by Letters Patent is:

A wire straightener comprising an open frame embodying spaced parallel sides and ends, sleeves axially alined and projecting 65 in opposite directions from the said ends, supports in which the sleeves are rotatably mounted, a plurality of disks carried in the frame and removably secured therein by means which hold them in spaced relation, 70 each disk being formed with a radial slot beginning at the center of the disk and terminating near the periphery, threaded plugs inserted in the disks on diametrically opposite sides, the said plugs being radially disposed and alined with the slots, jaws mounted in the slots and provided with shanks pivotally engaging in sockets formed in the plugs, wire receiving tubes carried between the jaws and disposed in the slots, and tubes 75 removably mounted in said sleeves, whereby the first said tubes may be thrown out of axial alinement with the last said tubes for the purpose specified.

In testimony whereof I affix my signature. 85
TORVAL E. VIK.
